UNITED STATES PATENT OFFICE

THOMAS C. PETRI AND DIXIE W. PETRI, OF NASHVILLE, TENNESSEE

IRONING BOARD

Application filed February 28, 1930. Serial No. 432,175.

Our present invention has reference to ironing boards, and our object is to provide an ironing board embodying novel features whereby the same can be attached to a table 5 of the usual construction to afford a strong and rigid structure and wherein the elements comprising the board may be readily removed from the table, separated and folded one against the other to produce a small 10 package for storage or for shipment.

To the attainment of the foregoing the invention consists in the improvement hereinafter described and definitely claimed.

In the drawings:

15 Figure 1 is a side elevation of the improvement.

Figure 2 is a top plan view thereof.

Figure 3 is a top plan view of the sleeve board.

20 Figure 4 is a top plan view of the ironing board.

Figure 5 is a substantially central longitudinal sectional view through the improvement in set up position.

25 Figure 6 is a sectional view approximately on the line 6—6 of Figure 5, with the sleeve board removed.

Figure 7 is a perspective view of the leg.

30 Figure 8 is a view similar to Figure 5 but illustrating a slight modification.

Figure 9 is an edge view of the upper portion of the leg disclosed by Figure 8.

The ironing board is indicated by the numeral 1 and has its rear edge centrally and longitudinally slotted, as at 2, for a determined distance. The top of the board at the opposite sides of the slot 2 is provided with penetrating elements 3.

The leg is indicated by the numeral 4. The leg has its outer edge provided with two spaced notches 5 and 6, respectively, and the inner walls provided by these notches are designed to afford straight shoulders when the leg is in operative position, the lower walls affording straight ledges, the same being disposed at right angles with respect to the shoulders. The outer edge of the leg 4, at a slight and suitable distance away from the notch 5 is provided with a notch 7 whose walls

are similar to the walls of the notches 5 and 6 although the walls are reversely arranged.

The leg 4 is adapted to be passed through the slot 2 in the ironing board 1 so that the inner wall or shoulder provided by the slot 5 will rest in the notch 5. The penetrating elements 3 are designed to be inserted in the under face of the top 8 of table and these elements are forced into the said table top by a pressure upon the outer end of the board 1. The board will be thus tilted on the shoulder 5 but in addition to this the said board will be tilted and canted upon the end of a brace prop 9 which affords a fulcrum as well as a support for the board, the said prop being pivoted, as at 10, to the leg 4. The free end of the brace prop 9 is received in a pocket 11 provided by a depression or by forming the under face of the board with a cavity. The prop is held in vertical position when in operation by contact with a stop element in the nature of a cleat 12 which is tacked or nailed to one side of the leg. The sleeve board is indicated by the numeral 13 and the same from its rear end is centrally provided with a longitudinal slot 14 for a determined distance. The inner wall provided by the slot is designed to rest in the notch 6 of the leg 4. The bifurcated portions 15 at the end of the board provided by the slot 14 have alining transverse substantially U-shaped groove 16 therethrough and these grooves are designed to receive therein a laterally extending pin 17 that is inserted through the leg adjacent to the top thereof.

With a simple construction as above described it will be noted that the ironing board may be set up in an easy and expeditious manner to afford a strong and sturdy structure which is also true with respect to the sleeve board. It will be further noted that the elements constituting the improvement may be readily removed from the table and folded one against the other to produce a small package for storage or for shipment.

In Figures 8 and 9 the construction slightly differs inasmuch as the leg 18 is hinged, as at 19, to the under face of the ironing board 20. The ironing board is provided with the longitudinal slot 21 that enters from its rear end 100

and may be provided with penetrating elements similar to the elements 3. The brace prop 20' is pivotally secured to the ironing board and is swingable against the inner and straight wall provided by a pocket 21' whose inner wall is arcuate, as indicated by the numeral 22. A stop cleat 23 may be secured to one side of the leg 18 for the brace prop 20' although this is not an absolute requirement. 5 The leg is provided with notches similar to the notches 5, 6 and 7 disclosed in the leg construction previously described and the upper shoulder 24 for the sleeve board 25 is in this instance arranged in a line with the upper and lower walls of the grooves 26 at the sides of 10 the leg 18. The slot in the end of the sleeve board is comparatively narrow so that the side walls provided by the slot will be received in the groove and in this manner the 15 sleeve board will be effectively supported 20 upon the leg 18.

It is thought the foregoing description when read in connection with the accompanying drawings will fully set forth the construction and advantages of the improvement so 25 that further detailed description will not be required.

Having described the invention, we claim:

An ironing board comprising a board having 30 a slot extending inwardly of one end thereof and having said end disposed under a table top, a notched leg extending through the slot with one notch thereof in engagement with the end wall of the slot and another notch receiving the edge of the table top, said board having a depression, a brace pivoted to the leg with the free end thereof fitting in the depression, and a cleat secured to the leg to be engaged by the cleat. 35

40 In testimony whereof we affix our signatures.

THOMAS C. PETRI.
